SUPERCHARGING MECHANISM FOR DIESEL ENGINES

Bruno Loeffler, Plainfield, N. J., assignor to Mack Manufacturing Corporation, a corporation of Delaware

Application June 4, 1935, Serial No. 24,824

3 Claims. (Cl. 123—30)

The present invention relates to Diesel engines and embodies, more specifically, an improved supercharging mechanism by means of which additional air may be introduced into the engine 5 during predetermined periods of operation thereof. It is well known that the power output of a Diesel engine varies directly as the amount of air introduced thereto, the amount of fuel which is burned being dependent upon the amount of 10 air supplied to support combustion. The power output of Diesel engines has heretofore been increased by providing supercharging mechanisms to supply the total air introduced into the engine at an increased pressure. The objection to 15 this form of supercharging lies primarily in the relatively great cost thereof due to the power required to compress and direct the entire air supply into the engine.

It is known that, during the normal operation 20 of a Diesel engine, and where supercharging mechanism is not provided, only about eighty-five per cent. of the air which would normally be directed into the engine is available by reason of the suction effect of the piston and other 25 losses due to friction, etc. In order that this loss of substantially fifteen per cent. may be retrieved, and substantially one hundred per cent. of the air normally available be supplied to support combustion, the present invention provides a 30 mechanism for introducing a volume of air corresponding to such loss at the proper time during the engine operation. This additional air is supplied through a separate channel and introduced into the engine in a particularly advantageous 35 fashion, as will be apparent presently.

It is a further object of the invention to provide a supercharging mechanism wherein additional air may be supplied to the engine during 40 predetermined periods of operation thereof, the means for supplying the air being of such character as to introduce as much air as possible during the time available for the introduction thereof during certain periods of operation of the engine.

45 A further object of the invention is to provide a supercharging mechanism wherein additional air may be introduced and supplied into the cylinder in such fashion as to supply the loss of air due to wire drawing through the inlet port 50 upon closing movement of the air inlet valve.

A further object of the invention is to provide a Diesel engine construction wherein combustion and air chambers are provided to improve the 55 operation thereof, the air chamber being additionally formed to serve as a means by which

additional, or supercharged, air may be introduced into the cylinder.

In the construction shown in the accompanying drawings, the invention is attained by the provision of an engine having a head in which combustion and air chambers are formed to communicate with the engine cylinder, the air chamber being formed to receive supercharged air from an external source, in addition to the fuel and air mixture which is directed into the combustion chamber during the compression stroke of the piston.

Further objects, not specifically enumerated above, will be apparent as the invention is described in greater detail in connection with the accompanying drawings, wherein

Figure 1 is a schematic illustration of a portion of the head of a Diesel engine embodying features of the present invention;

Figure 2 is an enlarged view in section, taken 20 through the combustion and air chamber shown in Figure 1, and showing the elements of the present invention in greater detail;

Figure 3 is a diagrammatic illustration of the manner in which air is introduced into the air 25 chamber, the illustration comprising a valve lift-time curve;

Figure 4 is a diagrammatic representation of the inlet and exhaust cycles of operation of an engine in which is incorporated the present invention;

Figure 5 is a plan view showing the cylinder head of the mechanism shown in Figure 1, illustrating the relative location of the engine valves.

With reference to Figure 1, a Diesel engine is 35 illustrated at 10 and provided with a head 11. The engine is formed with a cylinder 12 with which a combustion chamber 13 communicates, the combustion chamber in turn communicating through a port 14 with an air chamber 15 which 40 may be formed in a suitable housing 16 or which may constitute part of the engine head. The usual inlet and exhaust valve mechanism 17 and 18 is provided to introduce air and exhaust the products of combustion from the cylinder during 45 the operation of the engine.

Within the housing 16, a cylindrical valve 19 is 50 rotatably mounted, being provided with a port 20 which is adapted to align with port 14 to establish communication between the combustion chamber 13 and the air chamber 15. At the top of the cylindrical valve 19, a valve seat 21 is formed, the seat being masked by a cylindrical masking surface 22 in which a valve 23 is received. The valve is adapted to seat upon the 55

seat 21 and thus prevent the introduction of air into the air chamber. A lever 19' may be provided to rock the valve member 19 in a proper fashion during the operation of the engine, thus 5 enabling the air chamber to be disconnected from the combustion chamber during the starting operation.

Above the valve member 19 is a chambered head 24 within which the valve stem 25 of the 10 valve 23 is slidably mounted. The head 24 is provided with a passage 26 which communicates with any suitable source of air pressure as, for example, a pump or accumulator within which air is maintained under a predetermined pressure. 15

Inasmuch as air is introduced into the air chamber 15 when the valve 23 leaves the masking surface 22, a greater amount of air is introduced into the air chamber during the limited 20 time available than in a construction wherein no masking of the valve is provided. By masking the valve, the ordinate 28 (representing zero valve velocity) is advanced to the position indicated at 29. In this fashion, the time indicated 25 between the points 30 and 31 on the curve (representing the time during which the valve 23 establishes communication between the passage 26 and air chamber 15) witnesses a greater average valve area than with an unmasked valve.

Figure 4 represents diagrammatically the cycle 30 of operation of the engine, the inner annulus 32 representing the operation of the inlet valve 17 and the outer annulus 33 the operation of the exhaust valve 18. It will be observed that the inlet valve is closed at 20 degrees on return stroke. The shaded segment 34 represents the time during 35 which the supercharging valve 23 is open. In other words, the supercharging valve is open in advance of the closure of the inlet valve and is closed after the inlet valve has been closed. In this fashion, the air which would otherwise be lost due to wire drawing, through the air inlet port, is supplied at the end of the inlet stroke and the power output of the engine is thus substantially increased. 40

By providing the air chamber 15 with the mechanism above described, the air chamber not only serves as a means for improving the normal operation of the engine, but additionally 50 serves as a means for providing a supercharging

action which is independent of the main air supply introduced through the inlet valve. While the invention has been described with specific reference to the accompanying drawings, it is not to be limited save as defined in the appended 5 claims.

I claim:

1. In combination with a Diesel engine head having a combustion chamber formed therein and an air chamber communicating therewith, a source of air under pressure, a valve between the air chamber and combustion chamber, means to adjust the last-named valve, and a masked valve between the air chamber and the source of air, said masked valve moving away from the source of air during its opening movement and being formed to prevent communication between the chamber and source of air during initial motion of the valve toward an open position whereby the amount of air entering the chamber is increased upon initial flow thereof past the valve. 15

2. In combination with a Diesel engine head having a combustion chamber formed therein and an air chamber communicating therewith, a source of air under pressure, a cylindrical valve in the air chamber, means to rotate the cylindrical valve to control the flow of gases between the air and the combustion chambers, a valve port in the cylindrical valve coaxially thereof communicating with the source of air, a valve co-operating with the port, and a cylindrical wall adjacent the port on the side thereof adjacent the air chamber and of substantially the same size as the valve, whereby the last-named valve is masked to prevent communication between the chamber and source of air during initial motion of the valve toward an open position. 25

3. In combination with a Diesel engine having a cylinder and a head having a combustion chamber formed therein separate from, but communicating with, the cylinder, an air chamber, the head having a port between the air chamber and combustion chamber to afford communication therebetween, adjustable valve means to vary the communication between the air chamber and the combustion chamber, and an air inlet valve and valve seat, said last named valve seat being formed on the said adjustable valve means. 35

BRUNO LOEFFLER. 50
